(57) **CLAIM**

The ornamental design for a side structure for casegoods, as shown and described.

DESCRIPTION

FIG. 1 is a perspective view of a side structure for casegoods showing my new design;

FIG. 2 is a front elevational view thereof;

FIG. 3 is a side elevational view thereof;

FIG. 4 is a perspective view of a second embodiment of a side structure for casegoods shown in FIG. 1;

FIG. 5 is a front elevational view thereof;

FIG. 6 is a side elevational view thereof;

FIG. 7 is a perspective view of a third embodiment of a side structure for casegoods shown in FIG. 1;

FIG. 8 is a front elevational view thereof; and,

FIG. 9 is a side elevational view thereof.

The rear and bottom of the side structure form no part of the design.

The broken lines shown are for illustrative purposes only and form no part of the claimed design.
